Primary Examiner — Rhea Shields**CLAIM**

The ornamental design for a display screen with transitional graphical user interface, as shown and described.

DESCRIPTION

FIG. 1 is a front view of a first embodiment of the display screen with transitional graphical user interface;

FIG. 2 is a second image thereof.

FIG. 3 is a front view of a second embodiment of the display screen with transitional graphical user interface; and, FIG. 4 is a second image thereof.

In the drawings, the dot-dash broken lines are for the purpose of illustrating the display screen and forms no part of the claimed design. In the drawings, the dash-dash broken lines are for the purpose of illustrating portions of the transitional graphical user interface that forms no part of the claimed design.
